CLAIM

The ornamental design for a “information storage cartridge for electronic game machine,” as shown and described.

DESCRIPTION

FIG. 1 is a top plan view of an information storage cartridge for electronic game machine showing a first embodiment; FIG. 2 is a front elevational view thereof; FIG. 3 is a bottom plan view thereof; FIG. 4 is a rear elevational view thereof; FIG. 5 is a right side elevational view thereof; FIG. 6 is a left side elevational view thereof; FIG. 7 is a top, front and right side perspective view thereof; FIG. 8 is a bottom, rear and left side perspective view thereof; FIG. 9 is a top plan view of an information storage cartridge for electronic game machine showing a second embodiment; FIG. 10 is a front elevational view thereof; FIG. 11 is a bottom plan view thereof; FIG. 12 is a rear elevational view thereof; FIG. 13 is a right side elevational view thereof; FIG. 14 is a left side elevational view thereof; FIG. 15 is a top, front and right side perspective view thereof; FIG. 16 is a bottom, rear and left side perspective view thereof; FIG. 17 is a top plan view of an information storage cartridge for electronic game machine showing a third embodiment; FIG. 18 is a front elevational view thereof; FIG. 19 is a bottom plan view thereof; FIG. 20 is a rear elevational view thereof; FIG. 21 is a right side elevational view thereof; FIG. 22 is a left side elevational view thereof; FIG. 23 is a top, front and right side perspective view thereof; FIG. 24 is a bottom, rear and left side perspective view thereof;

FIG. 25 is a top plan view of an information storage cartridge for electronic game machine showing a fourth embodiment;

FIG. 26 is a front elevational view thereof;

FIG. 27 is a bottom plan view thereof;

FIG. 28 is a rear elevational view thereof;

FIG. 29 is a right side elevational view thereof;

FIG. 30 is a left side elevational view thereof;

FIG. 31 is a top, front and right side perspective view thereof;

FIG. 32 is a bottom, rear and left side perspective view thereof;

FIG. 33 is a top plan view of an information storage cartridge for electronic game machine showing a fifth embodiment;

FIG. 34 is a front elevational view thereof;

FIG. 35 is a bottom plan view thereof;

FIG. 36 is a rear elevational view thereof;

FIG. 37 is a right side elevational view thereof;

FIG. 38 is a left side elevational view thereof;

FIG. 39 is a top, front and right side perspective view thereof;

FIG. 40 is a bottom, rear and left side perspective view thereof;

FIG. 41 is a top plan view of an information storage cartridge for electronic game machine showing a sixth embodiment;

FIG. 42 is a front elevational view thereof;

FIG. 43 is a bottom plan view thereof;

FIG. 44 is a rear elevational view thereof;

FIG. 45 is a right side elevational view thereof;

FIG. 46 is a left side elevational view thereof;

FIG. 47 is a top, front and right side perspective view thereof; and,

FIG. 48 is a bottom, rear and left side perspective view thereof.
